UNITED STATES PATENT OFFICE

GEORGE R. BRENT, OF ORANGE, TEXAS, ASSIGNOR OF THIRTY-SEVEN AND ONE-HALF ONE-HUNDREDTHS TO EDGAR W. BROWN, JR., ELEVEN ONE-HUNDREDTHS TO W. E. LEA, TEN ONE-HUNDREDTHS TO CHARLES R. STEELE, AND FOUR ONE-HUNDREDTHS TO C. C. LEEDY, ALL OF CHICAGO, ILLINOIS

HYDRAULIC BRAKE

Application filed September 19, 1929. Serial No. 393,765.

This invention relates to a hydraulic brake mechanism.

It is aimed to provide a novel, generally improved, simplified, durable and efficient construction whereby any desired braking effect may be readily assured.

It is further aimed to provide a construction wherein braking blades coact with a cam shaped rotor and which rotor is provided with one or more passages to permit the escape of pressure past the blades adjacent the high points of the eccentric or rotor.

Another object is to provide a novel construction wherein the blades cannot all be retracted at the same time out of the path of movement of the rotor or cam to the end that a positive braking effect may always be realized.

Various additional objects and advantages will become apparent from a consideration of the description following taken in connection with accompanying drawings illustrating an operative embodiment.

In said drawings:—

Figure 1 is a view in elevation of one form of the braking mechanism,

Figure 2 is a cross sectional view taken on the line 2—2 of Figure 1,

Figure 3 is a vertical sectional view taken on the plane of line 3—3 of Figure 2,

Figure 4 is a sectional view taken on the line 4—4 of Figure 3,

Figure 5 is a vertical sectional view taken on the same plane as Figure 3 but through a modified form, and

Figure 6 is a detail sectional view taken on the line 6—6 of Figure 5.

Referring specifically to the drawings wherein like reference characters designate like or similar parts and first to the form shown in Figures 1 to 4, 10 designates a suitable casing which may comprise a ring 11 and side plates 12 bolted or screwed thereto as at 13. The casing 10 is air and fluid tight and is adapted to contain a quantity of oil or other fluid. Operating within the casing 10 is an eccentric, piston or cam 14 which is keyed or rigid on a shaft 15, extending through stuffing boxes 16 provided in the sides or plates 12. The shaft 15 is part of or extends

from the machine or article whose motion is to be braked. The invention is especially useful as a brake on oil well drilling machinery but no limitation in this connection is to be implied.

The piston 14 has extended peripheral surfaces at 17 which intimately wipe the inner surface of the ring 11. Such surfaces 17 are joined by arcuate cam surfaces 18 on the piston, and grooves 19 are provided in the surfaces 18, extending from the portions 17 to a distance therefrom and opening at the surfaces 18.

Housings 20 are formed by coacting parts of the ring 11 and plates 12 which slidably mount valves or gates 21, for radial movement and for coaction with the surfaces 18. The valves 21 have stems 22 which are slidably mounted in stuffing boxes 23 provided at the outer ends of the housings and coacting with the stems 22 are coil springs 24 which urge valves 21 outwardly to a retracted position beyond the inner wall of the ring 11 so that if desired they will not offer resistance to the travel or rotation of piston 14.

The valves 21 are each adapted to be moved inwardly at the same time and by the same mechanism which is diagrammatically shown as an arcuate member 25 having enlarged slots through which the stems 22 extend and with which the springs 24 engage. Said member 25 has cams 36 to engage the outer end of the springs 24 and the member is adapted to be shifted in an arc through rack and pinion gearing at 27, the springs 24 always serving to urge the valves 21 away from engagement with piston 14.

The positions of the valves 21 control the passage of fluid from one side of such valves to the other, in the chambers formed between each two adjacent portions 17, thereby regulating the braking effect in any desired manner on the piston 14, shaft 15, and parts controlled by the latter.

When the valves 21 reach the position shown by the uppermost one in Figure 3, the grooves 19 will permit the release of pressure from behind such valves 21, that is between the same and the high points 17,

overcoming any tendency of the valves to wedge or stick at the high points.

It will be noted that the valves 21 are pointed at the edges engaging the walls 18 of the piston. The fluid such as oil may be injected into the casing 10 through a suitable valve device at 25.

Attention is called to the fact that the arrangement of using three valves 21 and three cam portions 18, that it is impossible at any one time to have all of the valves retracted like the right hand one in Figure 3 which would render it impossible to immediately move one of them to a braking position.

A modified form is shown in Figures 5 and 6 which is similar in all material respects to the preceding form, differing therefrom only regarding the piston which is here designated 14' and which functions exactly like that at 14. The present piston is substantially oval shape and at its ends has more extended contact at 30 with the inner surface of the ring. But two cam surfaces at 31 are used corresponding to those at 18, and adjacent the ends thereof, grooves 32 are provided which function similarly to the grooves 19.

Various changes may be resorted to provided they fall within the spirit and scope of the invention.

I claim as my invention:—

1. An hydraulic brake device of the class described comprising a casing, a piston operable therein, a plurality of valves radially movable in the casing to coact with the piston and fluid contained in the casing, said piston having portions adapted to wipe the wall of the casing, and said piston having a pressure-release groove extending in a direction away from the wall and in the portion thereof engageable by the valves.

2. An hydraulic brake device of the class described comprising a casing, a piston operable therein, a plurality of valves radially movable in the casing to coact with the piston and fluid contained in the casing, said piston having portions adapted to wipe the wall of the casing, said piston having a pressure-release groove extending in a direction away from the wall and in the portion thereof engageable by the valves, said piston having three sides, and said valves being three in number.

55 In testimony whereof I affix my signature.
GEORGE R. BRENT.
